Primary Examiner — Jonathan J Han*Assistant Examiner* — Molly K. Orzechowski(74) Attorney, Agent, or Firm — Fross Zelnick Lehrman & Sissu, P.C.; Lawrence E. Apolzon, Esq.(57) CLAIM

The ornamental design for a sole for footwear, as shown and described.

DESCRIPTION

The SOLE FIGURE is a bottom view of a sole for footwear showing my new design.

The broken lines show portions of the sole for footwear, that form no part of the claimed design.

1 Claim, 1 Drawing Sheet(56)
